GREASE DISPENSING PAIL BASE

Edwin P. Sundholm, Albert City, Iowa, assignor
to Our Savior's Evangelical Lutheran Church,
Albert City, Iowa, a corporation of Iowa

Application July 24, 1947, Serial No. 763,225

6 Claims. (Cl. 226—125)

1

The present invention relates to certain new and useful grease-gun-loading pail-base or pump-loading pail-base, for receiving, at its top, an original and relatively thin-walled and inexpensive vendable merchandising container (namely, a container in which the fluid or semi-fluid is originally packed, shipped, stored and sold), as, for instance, an original thin-walled sheet-metal pail of lubricant (such as grease or viscous oil) or of printers' ink, caulking compound, etc., and for receiving, at its side, the reservoir-barrel of a grease-gun or the like or a pump-cylinder, whereby the lubricant or other viscous fluid may be conveniently loaded directly from the original container into the reservoir-barrel of the grease-gun or into the pump-cylinder through the intervention of the gun-loading pail-base of the present invention.

One of the further objects of the present invention is to provide a gun-loading pail-base or transfer-base which will be adapted to receive and operatively to engage a pail with a standard bottom flange with a standard seam-bead, and without any special bayonet lugs or projections.

One of the objects of the present invention is to permit the use of a more or less standard or conventional pail rather than requiring a special pail.

Other objects of the present invention will appear from the following description and the accompanying drawings, wherein I have shown, for the purpose of illustrating my invention, forms thereof which are at present preferred, although it is to be understood that the various instrumentalities of which the invention consists can be variously arranged and organized and that the invention is not limited to the precise arrangements and organizations of the instrumentalities as herein shown and described.

In the accompanying drawings, in which like reference characters indicate like parts,

Figure 1 represents a cross-sectional view of the pail-base with a pail engaged therewith and a grease-gun connected thereto.

Figure 2 represents a top plan view of the same pail-base as shown in Figure 1, but on a smaller scale, and is intended merely to indicate the circumferential distribution of the can-gripping means.

Figure 3 represents a fragmentary perspective view of a portion of one of the can-gripping jaws of the form of construction indicated in Figure 1.

Figure 4 represents a fragmentary vertical cross-sectional view of one of the can-gripping means in the base of the form of construction

indicated in Figure 1, but on a somewhat larger scale.

Figure 5 represents a similar fragmentary top plan view on a similarly enlarged scale.

Figure 6 represents a fragmentary perspective view of the can-gripping jaw of a modified or alternative construction.

Figure 7 represents a fragmentary vertical cross-sectional view of the can-gripping jaw of a modified form of construction represented by Figure 6.

Figure 8 represents a fragmentary top plan view of the pail-base (without the can-gripping jaw) of the form of construction represented by Figure 7.

In the drawings, the pail or can is generally designated by the letter C, while the base is generally designated by the letter B.

The bottom 11-a of the container C, is provided with a downwardly depending more or less cylindrical flange-like portion 11-b, which telescopes into the lower end of the cylindrical body 11-d of the container C, to a greater or lesser extent, depending upon the axial length of flange 11-b, and is secured thereto by an interlocking crimped seam 11.

The sheet-metal bottom 11-a, of the container C, may have pressed into it, in a downward direction (or in an upward direction), an annular groove 23, to form a doughnut-like ridge or annulus on the outside (or on the inside) of the bottom 11-a; the outer (or inner) more or less flat or rounded annulus-like surface 24 of which constitutes a seating-surface for making sealing-contact with an annular sealing-gasket or ring 25 (of cork, grease-resistant rubber or composition or other suitable resilient material) carried by the base "B". The annulus 23 is preferably centered, or approximately centered, in relation to the periphery of the bottom 11-a of the container C.

The annulus 23 also serves to stiffen the center of the bottom 11-a, so that a circular disc-like portion, within the center of the annulus 23, can be more readily cut out or knocked out by the cutting action of the cutters (as in the embodiment herein shown and described) or by any other suitable disc-removal operation. The annulus 23 also serves to center or guide the cutters or knives 26, during the cutting operation, and serves also to stiffen and reinforce the center of the bottom 11-a after the disc has been cut out or removed therefrom.

In one embodiment of the base of my present invention, illustrated in the drawings, the base

"B" may be formed of two members 22-a and 22-b, which may be welded to each other or may be interlocked by a seam 29, so as to form a generally unitary construction, in which each member supports and gives rigidity to the other, thereby permitting the two members to be formed (by pressing between dies or by spinning or by rolling, or the like) out of relatively thin sheet-steel as, for instance, 20 or 22 gauge sheet-steel for a base for a 25 lb. container, or other relatively thin sheet-metal, and yet maintaining adequate strength and rigidity in the finished base "B".

In the end-wall or "bottom" 22, a center aperture 31 is formed, and the material from the aperture 31 may be pressed or drawn upwardly to form a short upstanding tube-like cutter-supporting intake-flange or intake member 32, although this tube-like cutter-supporting intake-flange or intake member is preferably formed separately, as shown, in the drawings, and spot-welded or crimp-seamed to the aperture 31. The metal around the hole 31 may be pressed down in a downwardly extending annulus 33, forming an annular groove around the tube-like flange 32, for the reception and retention of the resilient and grease-resistant packing-gasket or sealing-ring 25.

From the partition-wall or "bottom" 22, a radial channel 34, of more or less U-shaped cross-section, is pressed, in a downward direction, from a point which includes the projected area of the hole 31 (and may also include the projected area of the annulus 33), which channel 34 extends laterally outwardly to the side-wall 30, at one point, so as to form a fluid-conducting passage-way or conduit in communication with the hole 35 which is ultimately formed in the bottom of the original container, pail or can "C," within the annulus 23 thereof, outwardly to the gun-receiving socket 36 formed in or affixed to the side of the base "B".

In the top wall 22 of the base "B," which may be either of the two-ply construction shown in the drawings or which may be of a single-ply construction, a plurality of bead-gripping or bead engaging jaws are provided, which are generally designated by the numeral 1 and which are preferably (though not necessarily) uniformly distributed around the circumference of the base.

One or more of these bead-gripping jaws may be stationary but at least one or more (and possibly all) of these bead-gripping jaws are radially movable or have radially movable and spring-urged bead-gripping claws, which are preferably pressed out of the sheet-metal of which these members are formed.

In one embodiment of the present invention slots or slits 3 are provided in the pail-base B, at its periphery, for each of the movable bead-gripping jaws or members, and these slots are of a width sufficient loosely to accommodate the thickness of the sheet-metal of which the bead-gripping member 1 is formed, and are of a length sufficient loosely to accommodate the horizontal width of the bead-gripping member 1.

In the form of construction illustrated in Figures 1, 3, 4 and 5, the slits or slots 3 may each be plain slits or slots of uniform width, throughout.

Each bead-gripping member 1 is formed with the lower portion 4, which extends into the interior of the base B through the slot 3, and the outer portion 5 which extends above base B, and the locking or limiting means to keep the bead-gripping member 1 in proper vertical disposition in relation to the base B.

In form of construction shown in Figures 1, 3, 4 and 5, this latter means may be in the form of a pair of wing-like lugs 6 bent or pressed from the vertical portion 5 of the member 1, and out of the plane thereof; these projections 6 bearing against the top of the base and serving to prevent member 1 from moving down into the base beyond the point indicated in Figures 1 and 4.

A helical compression spring 7 is interposed between the lower and more or less horizontal portion 4 of the member 1 and the under side of the top of the base 22. To keep the spring 7 safely in place, the cup-like sockets or spring-seats 8 and 9 may be pressed into the portion 4 and into the top 22, respectively, as shown in Figures 4 and 7.

The spring 7 urges the lower portion 4 of the bead-gripping member 1 downwardly, and as this member is pivoted loosely in the slot 3, the upper portion 5 thereof is moved radially inwardly in the direction of the arrow 10. This causes the claw 2 to engage above the laterally projecting bead 11 of the pail or can "C," in the manner indicated in Figure 1.

The uppermost portion 12 of the bead-gripping member 1 is preferably bent outwardly slightly, as indicated in Figures 1 and 2, so that by pressing more or less downwardly and upwardly on the inclined tab 12, the upper portion 5, together with the claw 2, can be made to move upwardly slightly against the force of the spring 7, so as to release its grip on, or engagement from, the bead 11 of the pail or can C. The tab 12 may be engaged by hand or by simply pressing down on it with the foot of the operator.

In assembling the form of construction shown in Figures 1, 3, 4 and 5, either the slots 3 are made wide enough to permit the slightly enlarged thickness of the spring-cup 8 to pass through it, so as to permit the lower portion of the member 1 to be threaded through the slot 3, and then the spring 7 inserted between it and the spring-cup 9, or both the claw 2 and the stop-lugs 6 may be held in the plane of the upper portion 5 until that portion has been threaded upwardly through the slot 3 and then the claw 2 and lugs 6 bent out of the plane of the member 1, so as to keep the member 1 in the position shown in Figure 4.

In the alternative form of construction representing another embodiment of the present invention, shown particularly in Figures 6, 7 and 8, the slot 3 has an enlargement in its width at 13, over something less than its full length, and the upper portion 5 of the bead-gripping member 1 is provided with lateral recesses 14, with a narrow throat 15 therebetween, of a dimension substantially equal to the longitudinal dimension 16 of the slot-enlargement 13, so that after the member 1 of the alternative form of construction shown in Figures 6 and 7 has been threaded through the long portion of the slot 3, it is forced into the shorter portion 13 of the slot so that the narrow throat 15 fits into the correspondingly dimensioned portion 13 of the slot and is then held in that position by pressing the side of the base B inwardly as at 17. By pressing the projection 11 inwardly, the member 1 is permanently held in the shorter portion 13 of the slot and the member 1 is thereby held in permanent vertical relationship to the base and yet loosely pivoted in the slot 13.

While in the accompanying drawings all the bead-gripping members are shown of the movable form, one or two of these can be made sta-

tionary, by simply forming one or more bead-gripping or bead-engaging members integrally with or welded to the periphery of the base B; in which event the pail or can C would first have its bead 11 slipped under the stationary bead-gripping member, so as to spring the movable bead-gripping member open sufficiently to permit the bead 11 to get beneath the claw 2 thereof.

In either event, however, the ultimate engagement or securing of the can C to the base B is accomplished by pushing the bottom of the pail or can C down onto the base B until the bead thereof passes by and is thereafter interlocked with the movable claw 2 (or claws 2) of the one or more movable bead-gripping members 1.

Having thus described my invention, what I claim as new and desire to be protected by Letters Patent is:

1. A fluid dispensing base for suction-dispensing viscous fluids through the bottom of a top-vented thin-walled original vendable merchandising container, said base adapted to receive and detachably to engage an original vendable merchandising container containing a more or less viscous grease or like fluid and said base comprising a bottom portion adapted to rest on any floor-like or generally horizontal surface and an upper generally horizontal dispenser and generally circular container-rest adapted to support a container in a generally upright position, a container-puncturing and container-sealing member operatively secured at the generally central zone of said container-rest, a conduit extending from the said container-puncturing and container-sealing member to and through the side of the said base, a suction-receiving socket on the side of the said base in communication with the said conduit for sealingly receiving and for making quick-attachable and quick-detachable engagement with the intake end of the barrel of a grease-gun or like suction-producing device, and a spring-tensioned and radially gripping can-engaging member pivotally mounted upon said base at the periphery of said base and having a portion above and a portion below the upper wall of said base, said member being adapted radially to engage the lowermost end of a can and detachably to lock the same to the base.

2. A fluid dispensing base for suction-dispensing viscous fluids through the bottom of a top-vented thin-walled original vendable merchandising container, said base adapted to receive and detachably to engage an original vendable merchandising container containing a more or less viscous grease or like fluid and said base comprising a bottom portion adapted to rest on any floor-like or generally horizontal surface and an upper generally horizontal dispenser and generally circular container-rest adapted to support a container in a generally upright position, a container - puncturing and container - sealing member operatively secured at the generally central zone of said container-rest, a conduit extending from the said container-puncturing and container-sealing member to and through the side of the said base, a suction-receiving socket on the side of the said base in communication with the said conduit for sealingly receiving and for making quick-attachable and quick-detachable engagement with the intake end of the barrel of a grease-gun or like suction-producing device, and a bead-engaging can-locking member pivotally mounted upon said base at the periphery of the said base and having a portion above and a portion below the upper wall of said base,

said member being for lockingly engaging the bead of a can to lock the can to the base.

3. A fluid dispensing base for suction-dispensing viscous fluids through the bottom of a top-vented thin-walled original vendable merchandising container, said base adapted to receive and detachably to engage an original vendable merchandising container containing a more or less viscous grease or like fluid and said base comprising a bottom portion adapted to rest on any floor-like or generally horizontal surface and an upper generally horizontal dispenser and generally circular container-rest adapted to support a container in a generally upright position, a container - puncturing and container - sealing member operatively secured at the generally central zone of said container-rest, a conduit extending from the said container-puncturing and container-sealing member to and through the side of the said base, a suction-receiving socket on the side of the said base in communication with the said conduit for sealingly receiving and for making quick-attachable and quick-detachable engagement with the intake end of the barrel of a grease-gun or like suction-producing device and a spring-tensioned can-locking member pivotally mounted upon said base at the periphery of the said base and having a portion above and a portion below the upper wall of said base, said member being for lockingly engaging the bead of a can to lock the can to the base.

4. A fluid dispensing base for suction-dispensing viscous fluids through the bottom of a top-vented thin-walled original vendable merchandising container, said base adapted to receive and detachably to engage an original vendable merchandising container containing a more or less viscous grease or like fluid and said base comprising a bottom portion adapted to rest on any floor-like or generally horizontal surface and an upper generally horizontal dispenser and generally circular container-rest adapted to support a container in a generally upright position, a container-puncturing and container-sealing member operatively secured at the generally central zone of said container-rest, a conduit extending from the said container-puncturing and container-sealing member to and through the side of the said base, a suction-receiving socket on the side of the said base in communication with the said conduit for sealingly receiving and for making quick-attachable and quick-detachable engagement with the intake end of the barrel of a grease-gun or like suction-producing device, and a can-locking member pivotally mounted upon said base near the periphery thereof and having a portion above and a portion below the upper wall of said base.

5. A fluid dispensing base for suction-dispensing viscous fluids through the bottom of a top-vented thin-walled original vendable merchandising container, said base adapted to receive and detachably to engage an original vendable merchandising container containing a more or less viscous grease or like fluid and said base comprising a bottom portion adapted to rest on any floor-like or generally horizontal surface and an upper generally horizontal dispenser and generally circular container-rest adapted to support a container in a generally upright position, a conduit extending from the generally central zone of said container-rest to and through the side of the said base, a suction-receiving socket on the side of the said base in communication with the said conduit for sealingly receiving and for making

quick-attachable and quick-detachable engagement with the intake end of the barrel of a grease gun or like suction-producing device and a can-locking member pivotally mounted upon said base near the periphery thereof and having the portion above and a portion below the upper wall of said base and a spring interposed between the lower portion of said can-locking member and a stationary portion of said base so as to urge the upper portion of said can-locking member into locking engagement with the can. 10

6. A fluid dispensing base for suction-dispensing viscous fluids through the bottom of a top-vented thin-walled original vendable merchandising container, said base adapted to receive and 15 detachably to engage an original vendable merchandising container containing a more or less viscous grease or like fluid and said base comprising a bottom portion adapted to rest on any floor-like or generally horizontal surface and an 20 upper generally horizontal dispenser and generally circular container-rest adapted to support a container in a generally upright position, a conduit extending from the generally central zone of said container-rest to and through the 25 side of the said base, a suction-receiving socket on the side of the said base in communication with the said conduit for sealingly receiving and for making quick-attachable and quick-detach-

able engagement with the intake end of the barrel of a grease gun or like suction-producing device, a slot in said base near its periphery and a can-locking member extending through said slot and loosely pivoted therein, said can-locking member having an upper can-gripping portion and a lower spring-tensioning portion, and a spring between said lower portion and a stationary portion of said base to urge the upper portion of said can-locking member swingingly into locking engagement with the can. 5
